UNITED STATES PATENT OFFICE.

RAYMOND V. LONG, OF RICHMOND, VIRGINIA, ASSIGNOR TO RICHMOND EQUIPMENT SUPPLIES, INCORPORATED, OF RICHMOND, VIRGINIA.

VENTILATION SYSTEM.

Application filed April 29, 1925. Serial No. 26,715.

This invention relates to ventilation systems and more particularly to a ventilation system for halls, schools, and the like, adapted to control the amount of air passing therethru in a uniform and efficient manner.

The ventilation of buildings, as for instance for school use, requires a definite volume of air per minute for each person

10 in a room, the required volume being obtained by providing a predetermined number of air changes per hour for each room of the building. Ventilation systems of the blower type have been designed to effect the necessary air changes, but this type of system involves an extensive installation and cumbersome ducts, together with extensive up-keep costs. In the forced air system, an undue waste of heated air thru the vent 15 ducts occurs, resulting in an over-cooling effect. The use of a straight steam installation, which is of the most common type, depending upon open window ventilation, is accompanied by many difficulties, mainly, 20 that of a temperature difference exceeding ten degrees, particularly when a wind is blowing directly against the windows from which the fresh air is taken, so that if any 25 fresh air is permitted to the room at all, a too great cooling effect, due to the over-abundance of air passing thru the room, results.

Therefore, one of the objects of my invention is to provide an efficient ventilation 35 system which automatically furnishes the necessary number of air changes while preventing an over-abundance of air passing thru the room to be ventilated.

A further object of my invention is to 40 provide a reliable ventilation system of the type particularly adapted for schools, in connection with a steam installation where the ventilation is dependent upon the opening of the windows, which system limits the 45 amount of heated air passing out of the room to the proper scientific volume required by each person occupying the room.

A further object is to provide in a simple 50 and practical ventilation system a vent check which, depending on the velocity of the heated air leaving a room, automatically provides the required number of air changes per hour without permitting an

over-abundance of air passing thru the room.

55 A further object is to provide in a ventilation system a vent check of the above described character which automatically limits the amount of air passing from a room depending on the velocity thereof, thereby to prevent an over-abundance of air passing thru the room.

60 A further object is to provide a device of the character described which is durable in construction, economical in manufacture and installation, efficient in operation, and which accomplishes among others the objects set forth.

65 The invention accordingly consists in the features of construction, the combination of parts, and in the unique relation of the various members and the relative proportioning and dispositioning thereof, all as more clearly outlined herein.

70 To enable others skilled in the art to fully comprehend the underlying features thereof, in order that they may embody the same, by numerous modifications in structure, and relation contemplated by this invention, drawings depicting a preferred form of the 75 invention have been annexed as part of this disclosure, and in such drawings like characters of reference indicate corresponding parts throughout all the views, of which—

80 Figure 1 is a view of a chamber, in perspective of a classroom type, having installed therein the proposed form of ventilation system.

85 Figure 2 is a view in perspective of the vent check.

90 Figure 3 is a sectional view taken on the line 3—3 of Fig. 2.

95 Figure 4 is an end view of the type of blade used in the vent check.

Figure 5 and 6 are details of the blade 100 stop devices.

Figure 7 is a detail of the bearing plate.

Referring now to the drawings and more particularly to Figure 1, the numeral character 10 designates a chamber such as a classroom, which is heated by a straight steam installation, the radiators 11 thereof being positioned below the windows 12. Air, entering the room over deflectors 13 arranged at the base of the windows, rises towards 105 the ceiling due to the steam radiators being

positioned below the deflectors. The freshly heated air is distributed about the room and passes therefrom under wardrobe doors 14 and thence thru a vent check 15 which is 5 hung from an opening in the ceiling of a wardrobe 16, and finally thru a duct 17 to a ventilator (not shown) on the roof of the building.

The vent check 15 (see Figures 2 and 3) 10 comprises a casing 20, substantially rectangular in form, and made preferably of galvanized iron with all joints riveted. Flanges 21 are provided at the top of the casing 20 for hanging the casing to the ceiling of the wardrobe 16 by any suitable means projecting thru holes 22.

A plurality of blades 24, of substantially S-shaped form (see Figure 4) are mounted within the casing 20 by means of axles 25 15 projecting thru center bushings 27 of the blades. The blades are made as light as possible, preferably of aluminum of a gage varying with the size of the vent check device. The rods or axles 25, preferably of 20 bronze, rest in bearings 28, positioned on the side walls of the casing 20, which are also preferably of bronze, and are fixedly joined to the casing 20 as by any suitable means such as rivets 30. Cut in the bearing 25 plates 28, are arcuate slots 31 (see Figure 7) 30 having a radius of approximately one and a half inches, in which the ends of the bronze rods 25 rest. These slots permit of a rolling bearing feature, as the rods 25 simply roll 35 in the bearings 28 as the blades 24 turn thru an arc of 90°, thus practically eliminating friction between these parts. In their normal open position, the blades extend in the direction of flow of air from the room to 40 permit a substantially free and unrestricted passage of the air thru the casing.

Referring to Figure 2, a plurality of small 45 holes 32 are provided in blades 24, across a half portion thereof. These holes permit of the balancing of the blades whereby they may be rotated about their center point upon a certain air velocity of the air passing thru the casing 20 being reached. Split shank bolts 35 are also provided, passing thru the 50 blades 24, and carry the nut or weight 36, as a means for further balancing the blades to turn at the proper air velocity. The bolts, after the blade has been properly balanced, are bent back into the dotted line position 55 (see Figure 4), to prevent the nut or weight 36 from loosening and dropping off. The velocities of air to which the blades are responsive are determined by the number of air changes found desirable so that the degree 60 of balance of the blades bears a direct relation to the number of air changes found to be best suited to particular needs.

The lower portion or inlet 37 to the casing 65 is angularly disposed with respect to the upper portion thereof, as shown in Figure 3,

and has mounted therein a plurality of baffles 38 arranged at an oblique angle of approximately 45° to the plane of the blades in their vertical position and in parallel relation to each other. The baffles 38 are designed to so direct the air against the blades so that the blades are operable to turn in unison and so that the air strikes the blades at sufficient angle to turn them, but at the same time the baffles do not seriously retard the flow of air thru the device. A relatively small space is provided around each blade to permit of some passage of air thru the ducts even when the blades are closed.

Mounted on the side walls of the casing 80 20 adjacent the bearing plates 28, are stop members 40 (see Figures 5 and 6) having their projecting arms 41 covered with shock reducing material such as piano felt, which is glued on and riveted to the arms 41. The felts are chemically treated or impregnated to prevent disintegration by moths, insects, and the like. It will thus be obvious that, due to the position of the stops, the blades 24 cannot revolve thru a greater arc than that of 90°, necessary to open and close the vent check. The underside of the vent check might advantageously be covered with a perforate protecting covering such as a wire mesh to prevent anything from hitting the 90 blades from below.

The operations of the system is briefly as follows: Air enters the room 10 at the base of the windows 12, and is deflected upwardly by means of the deflectors 13 and the positioning of the radiators 11 below the windows, from whence it is distributed about the room. As shown by arrows in Figure 1, air leaves the room beneath the wardrobe doors 14, passes thru the vent check 15 and duct 17 from whence it is discharged into the atmosphere. In its passage thru the room, the air attains a velocity dependent upon the amount of air entering the room and also upon the rate at which it is permitted to flow therefrom. It has been found that to provide each person in the room with sufficient volume of air per hour, it is necessary that a prescribed number of complete air changes per hour, usually 4 to 6, take place within the room. It will be seen from the above that by balancing the blades of the vent check to permit of the passage of air at a certain velocity from the room thru the vent duct 17 and to substantially close the vent upon a greater outflow velocity of the air being reached, the number of air changes permitted the room in an hour which is dependent upon the velocity of flow of air from the room may automatically be regulated. Thus, by determining the outflow velocity of air necessary to effect the desired number of air changes, per hour, and balancing the blades 24 to close the duct at any increased velocity, the vent duct will 110 115 120 125 130

- permit the air to pass therethru to allow freshly heated air to enter the room, but will automatically prevent any over-abundance of fresh air, due to the blades closing 5 the discharge of air from the room upon a greater velocity of flow than that as determined necessary, being reached.
- Further, the number of air changes permitted the room, may be varied by varying 10 the degree of balance of the blades 24 to close the vent duct within a given range of outflow velocities so that the vent check is operative within reasonable limits to effect various desired air velocities and air 15 changes.
- As hereinbefore stated, it is desirable to provide a space about the blades to permit some air to pass thru the device even when the blades are in closed position in order that 20 all ventilation is not cut off. This space is preferably such that approximately one complete air change per hour would take place if the blades were kept continuously closed which is sufficient to furnish a degree of ventilation 25 when the weather conditions are abnormal.
- The ventilation system as comprehended with the scope of the above described invention thus provides a simple and practical 30 means of providing the required volume of freshly heated air per person within a room and limits the amount of heated air passing from the room by means of the automatically operating vent check so that an over-abundance 35 of fresh air passing thru the room is prevented. As hereinbefore pointed out, the system is particularly adapted for use with a straight steam installation where ventilation is dependent upon opening of 40 the windows, but I do not wish to be limited in this respect, as it is obvious that the vent check is equally applicable and advantageous to other types of installations.
- In view of the above, it will be seen that 45 the several objects of the invention are achieved and other advantageous results attained. As many changes could be made in carrying out the above construction, without departing from the scope of the invention, it is intended that all matter contained in the above description or shown in the accompanying drawings shall be interpreted 50 as illustrative and not in a limiting sense.
- I claim:
- 55 1. A system of ventilation comprising means for admitting air into a room, and means for permitting air to flow from the room, said last mentioned means comprising a vent duct, a plurality of pivotally mounted blades positioned in the vent duct, said blades normally permitting flow of air from the room thru the vent duct, and operative to substantially close said vent duct when the flow of air thru the vent exceeds a 60 predetermined velocity, means to cause the air to flow to said blades at an oblique angle with respect to a plane thru the axes of the blade, and means permitting the return of said blades to normal open position when the abnormal outflow velocity is relieved. 70
2. A vent check adapted to be positioned in the air discharge duct of a room to provide a predetermined number of air changes in the room, comprising, in combination, a casing, and a plurality of balanced blades 75 pivotally mounted in said casing to normally permit a substantially unrestricted passage of air thru the casing, said blades being responsive to the velocity of air flow thru the duct from the room and means to so direct 80 air against said blades as to cause them to simultaneously swing in the same direction.
3. A vent check adapted to be positioned in the air discharge duct of a room, comprising, in combination, a casing, and a plurality of blades pivotally mounted in said casing provided with holes therethrough to assist in the balancing thereof, said blades being balanced and adapted to maintain a relatively vertical position upon normal velocity 85 of air outflow thru the casing, said casing being provided with means to cause the air to travel toward the blades at an oblique angle with respect to a plane through the axes of the blades, and to rotate about their pivot points to a relatively horizontal position to substantially close the vent duct upon an increase of velocity of air outflow, and stop members on said casing adapted to abut against said blades in their vertical and horizontal positions, thereby to limit the rotation of the blades. 90
4. A vent check adapted to be positioned in the air discharge duct of a room, comprising, in combination, a casing, a plurality 95 of substantially S-shaped blades, axles mounted substantially centrally in said blades, bearing plates on said casing having arcuate slots therein, said axles projecting into said arcuate slots whereby a rolling bearing for said blades is provided, said blades being balanced and responsive to the velocity of air flowing thru said duct. 100
5. A vent check adapted to be positioned in the air discharge duct of a room, comprising, in combination, a casing, a plurality of blades pivotally mounted in said casing, means to provide a rolling bearing surface for said blades with respect to said casing, means on said casing to limit the rotation of 105 said blades from a substantially vertical to a substantially horizontal position, means on said casing to direct the flow of air from the room at an oblique angle with respect to a plane through the axes of said blades, said blades being balanced to respond to the outflow velocity of air from the room, and thereby operative to check the flow of air from the room when the rate of outflow 110 exceeds a predetermined velocity and to 115
- 60 120 125 130

open the vent duct to the air outflow when the blades are relieved of excess outflow velocity.

6. A vent check adapted to be positioned in the air passage duct of a room comprising, in combination, a casing and a plurality of balanced blades pivotally mounted in said casing, said blades being responsive to the velocity of air flow from the room,

and said casing being provided with a plurality of angularly disposed baffles in parallel relation to direct the air against the blades at an oblique angle with respect to a plane thru the axes of said blades.

Signed at Richmond, Virginia, this 16th ¹⁵ day of April, 1925.

RAYMOND V. LONG.
